Patented June 1, 1915.

UNITED STATES PATENT OFFICE.

JOSEPH KISH, OF COBALT, ONTARIO, CANADA.

WRENCH.

1,141,715.

Specification of Letters Patent.

Patented June 1, 1915.

Application filed September 9, 1914. Serial No. 860,958.

To all whom it may concern:

Be it known that I, JOSEPH KISH, a subject of the King of Hungary, residing at Cobalt, Ontario, Canada, have invented certain new and useful Improvements in Wrenches, of which the following is a specification.

This invention relates to certain new and useful improvements in wrenches.

An object of the invention is to provide a wrench of the "Stilson" type with a pair of fixed jaws upon one side of the shank handle and provided with a pair of rack jaws, relatively movable and in alinement with the said shank handle.

15 A further object of the invention is to provide a wrench embodying rigid jaws that are movable by nut and thread connection and forming rack teeth on the outer end of the shank handle in combination with a movable rack member carried by the outer rigid jaw to provide pipe gripping means.

With the above general objects in view and others that will appear as the nature of the invention is better understood, the 25 same consists in the novel construction, combination and arrangement of parts to be hereinafter more fully described and then claimed, and in describing the invention in detail, reference will be had to the accompanying drawings by like characters designating corresponding parts throughout the several views, and wherein:—

Figure 1 is a side elevation of my improved wrench. Fig. 2 is an edge view of the same. Fig. 3 is a cross-sectional view taken on line III—III of Fig. 1. Fig. 4 is a cross-sectional view taken on line IV—IV of Fig. 1. Fig. 5 is a detail perspective view of the pivoted outer rack jaw.

40 Referring more in detail to the accompanying drawings, the reference numeral 10 designates the shank of the wrench with the handle 11 and as shown in Fig. 4, being preferably rectangular in cross-section.

45 The inner jaw member 12 is best illustrated in Fig. 5 having the outer face thereof roughened as at 13 to provide a gripping surface. The jaw member 12 is provided with a longitudinal opening 14, which opening is reduced as at 15 as shown in Fig. 5 to provide side members 16 to engage the sides of the rectangular shank 10 to prevent relative rotary movements of the jaw 12 and the said shank. The side members 16 are closed at their outer ends as at 17 to limit the inner

jaw in its swinging movement and further to provide a stop or contact for the flat spring 18 secured adjacent the outer end of the shank 10 with its free inner end engaging the said part 17. Alined openings are 60 provided adjacent the upper edge of the jaw 12 and through which extends a pin 20 constituting a pivotal support therefor, the said pin also extending through the shank 10 as best seen in Fig. 4. A second flat spring 21 65 is secured to the shank 10 and at its free outer end is in engagement with a cross pin 22 extending transversely of the jaw opening 14. It is to be noted that the springs 18 and 21 will limit in both directions the 70 pivotal movement of the inner jaw 12, and at the same time cushion the same to relieve the jaw of sudden shocks and jars.

The jaw 12 is mounted on the shank 10 as above described with the enlarged opening 14 positioned laterally of the shank and adapted to receive the grooved shank 22' of the outer jaw 23. Transverse openings 24 are provided in the inner jaw 12 and constitute a seat for the operating nut 25 80 through which the threaded shank 22 extends and by which the said shank is moved in an inward and outward direction. The outer jaw 23 consists of the rigid member 26 operating in connection with the gripping surface 13 of the inner jaw 12. The jaw member 23 is provided with a socket or recess for the reception of the stem 27 of a movable outer rack jaw 28. An annular groove 29 is formed in the stem 27 and receives the end of a fastening screw 30 threaded into the member 23, while the base of the said socket receives thrust bearing balls 31 to relieve the stem 27 of wear and afford an easy turning movement of the 90 rack jaw 28. The outer end of the shank 10 is provided with a rack jaw 32 coöperating with the pivoted outer rack jaw 28 and is particularly adapted for gripping round bodies or surfaces of irregular contour.

By providing the springs 18 and 21 and pivoting the inner jaw 12 to the shank 10, the jaws are relieved of undue strains by the cushioning effect of the said springs, 105 which will render the wrench more efficient in operation. It is to be noted that the rack jaws 28 and 32 are in alinement with the shank handle 10 which assures a stronger device and by pivotally-mounting the outer 110

rack jaw 28 as above described, the said rack jaws may readily adjust themselves to bodies of different shapes.

It is believed that the above description 5 of the invention will render the device clearly operative and while I have shown and described the preferred embodiment of the present invention, I do not wish to confine myself to the exact details of construction shown, as various forms, modifications 10 and arrangements of the parts as shown may be made without departing from the spirit and scope of the invention as claimed.

What I claim as new is:—

15 A wrench comprising a shank having a jaw at its outer end, a sleeve pivoted to said

shank, an outer jaw shank slidably-mounted in said sleeve, said outer jaw shank having a socket formed therein, an auxiliary jaw, a stem carried by the auxiliary jaw received 20 in said socket, ball bearings between the end of the stem and the bottom of the socket, said stem having a peripheral annular groove adjacent its end, and a retaining screw threaded into the outer jaw shank hav- 25 ing its inner end received in the stem groove.

In testimony whereof I affix my signature in presence of two witnesses.

JOSEPH KISH.

Witnesses:

JOSEPH BUDA,
W. F. MACPHIE.
